UNITED STATES PATENT OFFICE.

FRANK B. LAMBERT, OF CHICAGO, ILLINOIS, ASSIGNOR TO LAMBERT PROCESS COMPANY, OF CHICAGO, ILLINOIS, A CORPORATION OF ILLINOIS.

PROCESS OF BURNING BRICKS.

1,239,189.

Specification of Letters Patent. Patented Sept. 4, 1917.

Application filed March 20, 1915. Serial No. 15,910.

To all whom it may concern:

Be it known that I, FRANK B. LAMBERT, a citizen of the United States, residing at Chicago, in the county of Cook and State of Illinois, have invented a certain new and useful Improvement in Processes of Burning Bricks, of which the following is a full, clear, concise, and exact description, reference being had to the accompanying drawings, forming a part of this specification.

The invention herein described comprises an improved process of burning bricks. In my co-pending application Serial No. 681,720 I have set out a process for burning bricks, the present invention being an improvement on or refinement of the process set out in said application.

The invention disclosed in that application is the result of discoveries which I have made in experimenting with a specific type of clay, namely, the "hardpan" of the Chicago district. In that application I have made broad claims to the process.

The present invention is the result of discoveries made by me in applying the broad idea of the prior invention to other types of clay which required a definite manner of application of the broad invention to arrive at a successful result. This application sets out and claims the definite or specific manner of treatment which must be followed to insure success in burning.

The present invention enables me to decrease the time of burning a kiln very materially. It also enables me to carry on the process under proper control and it insures a product of high grade and uniform quality.

I have discovered that in burning bricks in accordance with the general method set out in my above-named application, the maintenance of a "pressure balance" which I shall hereafter fully describe, and the generation and holding of a "blanket of steam," which will also be described fully, to maintain the pressure balance between the inside and the outside of the kiln, allows me to carry out the process with much greater certainty, under perfect control, and at greatly increased speed of operation.

With the aid of the accompanying drawings, which form a part of this specification, I shall describe the specific manner in which my invention may be practised, although it

is obvious that the invention may be practised with variations and modifications to suit individual conditions.

Figure 1 shows diagrammatically in cross section a kiln of bricks with the burner placed in position and the burning operation begun.

Fig. 2 is a diagrammatic elevation of part of the kiln of brick, taken at right angles to Fig. 1.

Fig. 3 is a view similar to Fig. 1 showing the first stage of burning completed and showing the "induction pipe" put in place for "blowing".

Fig. 4 is a view similar to Fig. 2, illustrating this stage of burning.

Fig. 5 is a view similar to Fig. 3, illustrating the final step of burning when the blowing is about to be discontinued.

Fig. 6 is a view similar to Fig. 2 illustrating the stage of burning shown in Fig. 5.

The kiln shown in the drawings diagrammatically is a so-called temporary clamp kiln. In building the same, a layer of previously-burned bricks 1 is laid flat on the ground to receive the dried bricks which are set above. The dried bricks may be set either by machine, or by hand, as may be found convenient, and no special arrangement of the bricks is found to be necessary, although it is preferable that the same be set edgewise, in order to provide suitable space between the bricks for the draft for the fire.

The first part of setting the bricks in the kiln consists in placing the bricks in such position as to form the arches. These arches are placed about five or six brick-lengths apart and are usually about six or seven brick-widths in height. The bricks are usually piled in a kiln to a height of about 48 brick-widths, though it is understood that they may be stacked up to any convenient height, the kiln being about 30 arches long and about 52 brick-lengths in width. The outer courses of the kiln are composed of "double coal" bricks to take care of the heat losses which would occur by radiation due to exposure to the colder atmosphere. The thickness of the wall of double coal bricks is about the length of a single brick. These "double coal" bricks are made by mixing anthracite coal dust or

screenings with the clay before the same is run through the die. This layer of double coal bricks forms in effect an external furnace to supplement the internal furnaces which are formed by the arches. The theory of the external furnace thus formed is not that the same adds materially to the quantity of heat imparted to the kiln (though I wish it to be understood that the amount of heat generated by the burning coal in these bricks is very considerable) but rather that of forming a blanket or insulator for the heat within the kiln. It is well known that heat of its own energy travels only from a body of high temperature to one of lower temperature, and, inasmuch as the wall of burning double coal bricks is slightly hotter than the bricks inside, practically no heat from the inner bricks escapes to the outside, and the process is carried out evenly through the entire kiln. Outside of the layer of double coal bricks 2 is placed a layer or wall of previously-burned bricks 3, which is thicker for its lower half than for the upper half. The lower half is about a brick length in thickness, while the upper half is about a brick width in thickness. The bricks in this wall are closely piled together and after the same is finished the outer faces of the side and end walls are plastered over, with a daubing of clay or loam, so as to close off the outer air by plugging up all the cracks and crevices. A layer of previously-burned bricks may be placed on top of the kiln, but the same are not daubed and the gases and water smoke from the kiln are free to escape between the fissures and the openings of the upper layer of bricks. The outer wall 3 of burned bricks is built across the upper end of the arches, as indicated in the figures, and extensions 5 of the wall 3 are built around the openings to form what are called "dog houses." A peephole 10 formed in the outer wall 3 allows the attendants to observe the action inside of the arch. The side walls of the kiln may be braced against the posts or side of the shed within which the kiln is constructed. The end wall may be similarly braced, or may be braced by props or struts, as is well known in the art.

On top of the kiln, at regular intervals, are placed a pile or brickbats, or a single brick 12, which just touches an iron rod 11, which serves as a gage point for determining the "settle" of the kiln. The rod 11 may be secured in any suitable manner to the shed within which the kiln is constructed.

After the kiln is properly set up the burners 13 are put in place at each of the dog houses. This burner may be of any convenient type, but I prefer to employ a burner of the general type shown in my prior application, Serial No. 681,720. The burner is adapted to employ liquid fuel, which is furnished from a pipe 14 through a valve 15

and a flexible tube 16 to the casing of the burner itself. Steam for atomizing the liquid fuel and for driving the same into the kiln is supplied by the pipe 17, which is connected through a valve 18 and a flexible tube 19 to the body of the burner 13. The burner 13 is provided with a hand wheel and a needle valve for regulating the amount of liquid fuel, and is provided with an adjustable nozzle for regulating the amount of steam employed. As shown in Fig. 1, a burner is placed at each end of an arch and is adapted to drive the flame therefrom through the dog house 5 adjacent thereto, into the arch and the kiln of bricks above it. To start the burning operation, a brick 20 is placed in the arch adjacent each dog house, so that the flame from the burner 13 will impinge thereagainst. The purpose of this brick is to form a sort of baffle in order to cause the flame to spread at this point and to heat the adjacent unburned bricks and to start the double coal bricks burning slightly in advance of the main body of the bricks, as it is desirable that these bricks be burned slightly faster than the main body of the bricks. As soon as the bricks adjacent the dog house are brought to the desired temperature, the baffle brick 20 is removed and the flame from the burner 13 is allowed to travel laterally so as to heat the lower course of bricks.

It is to be noted that as soon as the outer part of the arch is brought to the desired temperature, the fire is forced to the limit in order to cause the heated zone, which extends only a slight way from the dog house toward the middle of the kiln, in a horizontal direction, to extend entirely across the bottom of the kiln. This is necessary in order to keep the burning under proper control. If the fire be advanced slowly the tendency will be to allow the heated vapors and flames to rise up through the bricks before the entire lower course becomes heated. If the incandescent zone be not made to extend completely across the lower courses, the fire will gradually create a draft through the kiln of bricks adjacent to the outer wall, somewhat as indicated by the dotted lines 21 in Fig. 1. The effect of this would be to allow an escape for the products of combustion and it would be practically impossible to burn the central core of the kiln, inasmuch as the tendency of the heat would be to escape through the path defined by the dotted lines 21. This has been one of the chief difficulties in previously-known processes for burning bricks.

As previously stated, the purpose of forcing the fire is to cause the zone of incandescence to extend evenly across the bottom of the kiln substantially at right angles to the general course of escape of the products of combustion, which is through the kiln 13.

and out the top. The fire is forced in through the dog houses with as great velocity as can be used with the resistance offered by the damp fire box and without carrying 5 too much back fire through the dog house itself. Due to this forced firing, a peculiar result is accomplished, which is very beneficial in the process of burning bricks. First, the vapor, or water smoke, as it is termed 10 by the attendants, is driven off from the bricks faster than the regular kiln draft can carry it away. As a consequence, it forms what is known as a blanket of steam above the incandescent zone. Hence, due to the 15 rapid firing, the draft immediately above the incandescent part is so greatly impeded as to be practically shut off and the escape for the products of combustion is easier 20 through the central part of the kiln, which is shown in the shaded central part in Fig. 1. As the products of combustion escape through the central part of the stack, the incandescent zone will be advanced in that direction and, as a consequence, at the end 25 of a certain period, which varies with the moisture content of the brick and with the steam pressure upon the burner, a complete blanket of steam will be formed above the incandescent zone and the draft through the 30 entire kiln will be impeded by this so-called blanket of steam. When this action occurs the entire lower course of bricks is necessarily at incandescent temperature, inasmuch as the incandescent state is what 35 brings about the blanket of steam. As a consequence the kiln will settle, inasmuch as the central part, which would tend to support the same, has also become softened with heat, and a slight settle over the entire top 40 of the stack may be observed. At this stage of the burning the use of the burners for supplying fuel is discontinued. It is to be noted at this point that, due to obtaining an incandescent zone extending entirely across 45 the bottom of the kiln, the settle of the kiln is not detrimental to burning and does not cause breakage of the bricks, as would be the case and as has been the case in burning bricks according to previously known processes. If the fire were allowed to burn 50 slowly and take its course upward between the heavy dotted lines 21 as shown in Fig. 1, a settle would eventually occur which would tend to break the bricks extending 55 across these dotted lines 21, inasmuch as the bricks defined by these lines are incandescent and the bricks in the part toward the center of the stack are still practically green or unburned and are slowly heated up by the 60 fire. It can also be seen that it will take a much longer time for the fire to reach the central core, or inverted cone-shaped portion, if the fire is once allowed to escape, as between the dotted lines 21. 65 Fig. 3 illustrates the stage of burning at

which the zone of incandescence extends across the bottom of the kiln. At this point, as above described, the use of fuel is discontinued and the "induction pipes", which are described and claimed in my co-pending application Serial No. 15,909, filed March 20th, 1915, are then inserted in the arches and the burners which now form steam jets are connected thereto, to blow a blast of steam into these pipes 22, which have openings 23 at 70 regular intervals, to direct the steam and induced air blast upward into the kiln. 75

The burners 13 need not all be shut off at the same time as it is desirable under certain circumstances to continue firing longer in some parts of the kiln than others, due to the difference in condition. 80

Before proceeding further, I shall describe more in detail the so-called "blanket of steam" which is formed above the incandescent zone in the kiln. The green bricks above the incandescent zone being piled into close proximity and presenting no direct avenue of escape for the gases therethrough, form a most efficient condenser 85 for condensing the vapors and moisture in the air and products of combustion which rise through the kiln. The green or unburned bricks are relatively cold and wet and tend very quickly to chill and condense 90 the moisture which is entrained in the air and products of combustion, and, due to this condensing action, as well as due to the fact that the pressure at this point is considerable owing to the driving off of 100 moisture from the bricks below, a very considerable impedance to the flow of air or products of combustion through the kiln is offered. The moisture which comprises this 105 blanket of steam comes not only from the water which is driven off from the green bricks, but is present due to its formation in the process of burning the hydro-carbon fuel, and due, also, to the dehydration of certain of the chemical constituents of the 110 bricks themselves. It can thus be seen that the air or products of combustion which pass upward from the incandescent zone are very heavily laden with moisture, and contact with the relatively cold green bricks 115 tends to condense the moisture, and, as is well known, a mist or condensing vapor is very thick and cohesive in comparison with a gas or superheated vapor.

When the fire is shut off at the burners 120 13, the kiln itself contains a certain number of heat units which are now utilized in burning or bringing to the desired point of fusion the remainder of the kiln or stack of 125 bricks. The result which is now to be described is not ascribed solely to the amount of heat imparted to the lower course of bricks, but it appears to be true that this preliminary heating is absolutely necessary in carrying out the process and in getting 130

the kiln into a proper condition whereby the remainder of the bricks may be burned according to this process.

As soon as the induction pipes 22 are placed in position in the arches, the dog houses may be partially closed off to regulate the amount of air passing into the kiln and the steam is then turned on through the burners 13, great quantities of steam and air being forced through these induction tubes up through the zone of incandescence into the main body of the kiln. I have found that the use of the induction tubes is not absolutely essential as the air may be swept in by the force of the steam jet through the openings of the dog houses. The induction tubes serve as means aiding in efficiently injecting and distributing the air and the steam. In such case it is not absolutely necessary to shut off the fire completely but the same may be merely reduced and the preponderance of steam and air made so great as to carry out the process. The final result is that the zone of incandescence travels upward in the general direction of the line of escape of the products of combustion until, at the end of a given time, which varies with the kind of clay of which the bricks are composed, the amount of draft, the size of the kiln, and so on, the zone of incandescence will have been driven up through the entire stack and will have reached the top thereof. At this point the blowing is discontinued and the kiln is allowed to cool, after which the same is a finished product, as the burning is completed.

The precise action involved in the step of causing the heat to traverse the entire kiln is somewhat obscure, but the general principle is that of the fireless cooker. A certain amount of heat has been put into the kiln at one part thereof and this heat is caused to act in turn upon the entire stack. The maintenance of the blanket of steam ahead of the zone of incandescence appears to be essential in order to conserve and to prevent spreading or dissipation of this zone of incandescence over too great an area or at too rapid a rate. The air which is introduced in with the steam serves to support combustion of the carbonaceous matter in the bricks themselves, and serves also as a medium for carrying the moisture, as it is well known that air acts as a sort of sponge to take up moisture and carry the same along with it. After the air and products of combustion have passed through the zone of incandescence, the moisture which has become entrained in these gases is again given up above the zone of incandescence, due to the condensing action previously described, and the blanket of steam is maintained not only by driving off the water vapor from the bricks themselves, but by the steam which is carried in the air and by the water which

is driven off in the process of dehydrating certain of the chemicals present in the bricks themselves. It has been found that the use of steam for producing the blast is not absolutely essential in certain cases, but it is undoubtedly true that this steam aids very materially in most instances in furthering the proper action. This may be due to the fact that the steam in going through the zone of incandescence is dissociated into its constituents, namely, each molecule breaks up into two atoms of hydrogen and an atom of oxygen. An atmosphere of dissociated steam would comprise, therefore, two parts of hydrogen and one part of oxygen by bulk or volume. For the oxidation of certain of the chemical components of the clay, it is obvious that this atmosphere, having one-third oxygen by volume, is better adapted than the atmospheric air which comprises essentially four parts of nitrogen to one part of oxygen by volume, and the molecular pressure of oxygen in an atmosphere of dissociated steam would be twice as great as in an atmosphere of atmospheric air.

It is to be noted throughout that I maintain a "pressure balance" inside the kiln at all times in carrying out this process. The firing by the burners is under forced draft, at all times sufficient to create enough pressure in the furnace to expel any air except that used for combustion. The pressure in the kiln is always slightly greater than the pressure outside, due to the expansion of the air caused by burning fuel, and due also to the pressure caused by the velocity head of the steam. While firing is carried on, it can be noted on the outside of the kiln that there is no leakage of air inward into the kiln through the outer wall 3. If any small holes exist in this wall 3 the escape of water smoke, or products of combustion may be noted at all times. The blowing by the steam nozzle and induction pipe is carried on at a velocity sufficient to supply the pressure formerly caused by the expanding air which was previously supplied in firing by the burners, and is also sufficient to force the incandescent zone and the blanket of steam through the kiln. As a result of this continuous pressure there is very little dissipation of the heat originally put into the kiln, there is practically no loss of draft, and the control that the operator has over the continuation of the process is practically absolute. That is to say, the burning cannot "get away" from the operator if he employs reasonable care.

While I have described the carrying out of my process with considerable detail, in order to make clear to those skilled in the art the manner in which the same is to be practised, I do not intend that my invention shall be limited to the precise steps or proportions

or times above indicated, as the same will vary to fit individual conditions, and I consider such variations and adaptations to fit particular circumstances such as will at once be apparent to those skilled in the art, to come within the spirit and scope of my invention.

What I claim as new and desire to secure by Letters Patent of the United States is:

1. The process of burning bricks which consists in setting the same in a kiln to have an internal furnace, then heating the furnace with fuel under forced draft sufficient to create enough pressure in the furnace to expel any air except that introduced for combustion, and at a rate sufficient to evaporate the water in the bricks faster than the kiln draft will carry the same off, thereby causing a damper of steam to form between the heat zone and the exit of the products of combustion, the fire being forced to cause the generation of a zone of incandescence substantially at right angles to the general line of travel of the products of combustion, said zone being brought to the temperature of fusion, then substantially discontinuing the firing by fuel and continuing the forced draft to fill the furnace and to maintain a pressure balance between the inside and the outside of the kiln, thereby moving the zone of incandescence and the blanket of steam ahead of it through the remainder of the kiln.

2. The process of burning bricks which consists of setting the bricks into a kiln, firing said bricks under forced draft the rate of firing being such as to create a slight pressure above atmospheric at the base of the kiln, and of such intensity as to create a zone of incandescence lying at substantially right angles to the general travel of the products of combustion through the kiln, and a body of steam above the zone of incandescence for preserving the heat in that zone, blowing an excess of steam and air into said zone of incandescence to cause the same to move in the general direction of the line of movement of the products of combustion until said zone of incandescence has been caused to travel the entire height of the kiln, and shutting off the fuel prior to the time that the zone of incandescence has traveled the entire height of the kiln.

3. The process of burning bricks which consists in setting the unburned bricks into a kiln having an internal heating chamber therein, then burning fuel under forced draft at such a speed as to drive off the moisture from the unburned bricks, at a greater rate than the same is carried off by the kiln draft, to bring to the temperature of vitrification a stratum of said bricks adjacent to said heating chamber and extending substantially at right angles to the line of travel of the products of combustion,

then cutting off the fuel and continuing the forced draft with such pressure as will maintain within the kiln a greater pressure than the atmospheric pressure outside, thereby driving the heat from said heated stratum to the adjacent strata of unburned bricks to drive off the moisture and bring them to the temperature of vitrification in progression.

4. The process of burning bricks which consists in setting the same in a kiln forming internal furnaces, then burning fuel under forced draft in said furnaces, said forced draft being maintained with sufficient pressure to drive off the moisture from the unburned bricks at a greater rate than the kiln draft will carry the same off, to create a blanket of steam above the zone of the fire, the fire being continued until there is created a stratum of incandescent bricks adjacent said furnaces, then substantially discontinuing the fuel supply and continuing the forced draft to cause the zone of incandescence and the blanket of steam to travel to an adjacent stratum of unburned bricks and bringing the same to the temperature of fusion.

5. The process of burning bricks which consists in setting the same in a kiln forming internal furnaces and firing said furnaces with fuel under a forced draft sufficient to cause the water smoke and other vapors to move from the stratum adjacent the furnaces at a greater rate than the kiln draft will carry the same off, and directing the fire in said furnaces to extend the heat zone in a substantially isothermal zone across the kiln and heating the bricks in said zone to the temperature of fusion, then substantially discontinuing the firing and continuing the forced draft to drive the blanket of steam forward from adjacent strata and causing said heated zone to travel successively to said strata, to bring to the temperature of fusion the adjacent unburned bricks in said kiln.

6. The process of burning bricks which consists in setting the bricks in a kiln forming internal furnaces, then heating the furnaces with fuel burned under a forced pressure draft, said fire being great enough to drive the water smoke and other vapors from the lower stratum of bricks adjacent the furnaces at a greater rate than the kiln draft will carry them off, thereby forming ahead of the heated zone a blanket of steam, said firing being carried on at such a speed as to prevent the entry of air into the kiln other than that introduced for supporting combustion, said firing being continued until said lower stratum is brought to the temperature of fusion, then substantially discontinuing the firing and continuing the forced pressure draft at a speed sufficient to maintain a pressure balance in said kiln

and to move said blanket of steam forward from said incandescent zone, and causing said incandescent zone to travel to successive strata continuously until the desired 5 temperature of vitrification shall have been attained by said adjacent strata.

7. The process of burning bricks which consists in setting said bricks into a kiln forming furnaces therein, then firing said 10 furnace with liquid fuel by means of a steam jet to create a forced pressure draft, said forced pressure draft being sufficient to cause a pressure inside of said kiln to exclude air therefrom other than that introduced to support combustion of the liquid fuel, said firing causing the water vapor to be driven off from said lower stratum of 15 bricks at a greater speed than is possible for the kiln draft to carry off the same, un-

til a highly heated, substantially isothermal zone is attained in the stratum adjacent said furnace, the bricks adjacent said zone being still at the temperature at which they give off water smoke and other vapors, then substantially discontinuing firing and maintaining the forced pressure draft by discharging jets of steam in said furnace at a rate sufficient to maintain a pressure in said kiln slightly above atmospheric pressure, thereby causing said highly-heated zone to travel from the lower stratum to adjacent higher strata. 20 25 30

In witness whereof, I hereunto subscribe my name this 12th day of March A. D. 1915.

FRANK B. LAMBERT.
